(57) **CLAIM**

The ornamental design for a lighting fixture, as shown and described.

DESCRIPTION

This application is related to commonly assigned, co-filed U.S. design patent application Ser. No. 29/791,194, filed on Jan. 4, 2022, by Roslyn J. YANDO, entitled “Lighting Fixture”; commonly assigned, co-filed U.S. design patent application Ser. No. 29/791,195, filed on Jan. 4, 2022, by Roslyn J. YANDO, entitled “Lighting Fixture”; commonly assigned, co-filed U.S. design patent application Ser. No. 29/791,192, filed on Jan. 4, 2022, by Roslyn J. YANDO, entitled “Lighting Fixture Pendant”; commonly assigned, co-filed U.S. provisional patent application No. 63/266,393, filed on Jan. 4, 2022, by Roslyn J. YANDO, entitled “Lighting Fixture Pendants”, which applications are incorporated herein by reference in its entirety.

FIG. 1 is a front right perspective view from below of a lighting fixture according to the new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top view thereof; and,

FIG. 7 is a bottom view thereof.

The broken lines in the drawings illustrate portions of the environment and the lighting fixture and that form no part of the claimed design.

1 Claim, 7 Drawing Sheets
